United States Patent

Des. 240,426
Patented July 6, 1976

240,426

FISHING LURE

C. Paul Haven, Beaver Dam, Ky., assignor to Nationwide Lure Manufacturing Co., Inc.

Filed Oct. 2, 1975, Ser. No. 619,012

Term of patent 14 years

Int. Cl. D22—05

U.S. Cl. D22—27

FIG. 1

FIG. 3

FIG. 2

FIG. 1 is a top plan view of the claimed fishing lure design;

FIG. 2 is a view in side elevation of the claimed design of FIG. 1, where the opposite side thereof is a mirror image; and

FIG. 3 is a perspective view showing further details of the claimed design.

I claim:

The ornamental design for a fishing lure, as shown and described.
